UNITED STATES PATENT OFFICE.

OTTO LUDVIG ZEUTHEN, OF BAGSVAERD, DENMARK.

MACHINE FOR DIGGING POTATOES.

Application filed February 3, 1921. Serial No. 442,079.

To all whom it may concern:

Be it known that I, OTTO LUDVIG ZEUTHEN, a subject of the King of Denmark, residing at "Det blaa Hus", Bagsvaerd, in the Kingdom of Denmark, have invented certain new and useful Improvements in Machines for Digging Potatoes, of which the following is a specification.

The present invention relates to a machine for digging potatoes and cleaning these from earth and roots and thereupon filling the potatoes into baskets or sacks.

In the accompanying drawing a constructional form of the machine is shown.

Fig. 1 is a side elevation in which, for reason of greater simplicity, some parts have been omitted.

Fig. 2 is a top view of the machine, in which likewise some parts have been omitted.

Fig. 3 is a section on the line 3—3 in Figs. 1 and 2.

Fig. 4 is a section on the line 4—4 in Figs. 1 and 2.

25 The potato-digger is drawn by horses or a tractor engine so that the wheels A, which are provided with grapples and are fitted to a shaft B, will run with a row of potato-plants between them. The shaft B runs in bearings f, which are fitted to a frame D, and drives by means of a bevel gear E another bevel gear F. This bevel gear F is fitted to the one end of a shaft J extending through the centre of the drums G and H.

35 The said shaft J is journalled in bearings K and L which are likewise fitted to the frame D. The bearing L has a pin which fits into a slot M in the front part O of a sack-truck N, Fig. 4, and which, on the other

40 side of this front part terminates in a handle P, to which a spring-operated catch Q is attached. By means of the handle P a man standing on the sack truck can lift or lower the plough-share S. This adjust-

45 able plough-share is fitted to the frame and will dig-up earth and potatoes, which are conducted into the drum G. This drum consists of a number of iron rods, fitted to the frame and bent in such a manner that

50 they form a cylinder, open at one side, concentrical around the shaft J. The said rods are disposed at such a distance from each other that earth and small stones, but no potatoes can drop through between them.

55 On the shaft J are fitted a plurality of sleeves T, which carry oblique blades or

shovels U which, when the shaft revolves in the direction of the arrow (Fig. 3) will break up the earth and force it through the spaces between the rods, or drive it, together with the potatoes, rearward towards the drum H. The hooks a, which are pivoted on a pin b and are by means of springs held in the position shown in Fig. 3, serve to break up the potato plants with the potatoes hanging thereto when, at the rotation of the blades, these are carried around. The opening in the side of the cylinder, seen in Fig. 3, is provided for the said plants and roots, which are carried round by the blades, to be ejected through it.

The drum H is made of the same diameter as the drum G and is likewise composed of a plurality of rods disposed with spaces between them, but these rods are secured 75 to arms C which are secured to the shaft and revolve with it. When the potatoes or larger stones are conducted by the blades U into the drum H, they will be lifted by shovels d fitted to the said arms C, up to 80 a shoot e and will fall into the latter. A flange screen p is provided to prevent the potatoes from falling out from the drum. From the shoot e they slide down into a sack, basket or the like secured on the sack-truck N. The latter sack-truck may be made so wide, that two men can stand on it, namely one to attend to the sacks, and the other to pick the stones from the shoot.

I claim:

1. A potato digging machine comprising a wheel frame, a plowshare supported by said frame, a skeleton cylinder fixed on said frame and adapted to receive potatoes released by said plowshare, said fixed cylinder being open at its rear end, a longitudinal shaft supported on said frame and driven from the supporting wheels thereof, a rotary skeleton cylinder supported on said shaft and provided with an open forward 90 end which registers with the open rear end of said stationary skeleton cylinder, a series of oblique blades supported by said shaft within said stationary cylinder and operative to pass the potatoes through the 95 rear end opening of said stationary cylinder into said rotary cylinder.

2. A potato-digging machine consisting of a frame running on wheels, a shaft longitudinally journalled on said frame, means 100 for driving said shaft from the said frame wheels, a plough-share adjustably attached

to said frame, a series of rods arranged around said shaft and bent to form a cylinder concentric to said shaft, and having an opening at one side, said rods being disposed with spaces between them, a series of oblique blades fitted to said shaft within said cylinder, a series of arms fitted to the shaft behind said cylinder, rods attached to said arms and bent to form a cylinder concentric to said shaft and of the same diameter as the first cylinder, and adapted to revolve with said shaft, shovels on said arms adapted to lift potatoes and stones, a discharge shoot for receiving the potatoes from said shovels and conducting them out of the machine, and a flange at the end of the second cylinder preventing the potatoes from falling out, and a low truck to carry the sacks and the crew for attending the machine and sacks.

3. A potato-digging machine consisting of a frame running on wheels, a shaft longitudinally journalled on said frame, means for driving said shaft from the said frame wheels, a plough-share adjustably attached to said frame, a series of rods arranged around said shaft and bent to form a cylinder concentric to said shaft, and having an opening at one side, said rods being disposed with spaces between them, a series of oblique blades fitted to said shaft within said cylinder, a series of arms fitted to the shaft behind said cylinder, rods attached to said arms and bent to form a cylinder concentric to said shaft and of the same diam-

eter as the first cylinder, and adapted to revolve with said shaft, shovels on said arms adapted to lift potatoes and stones, a discharge shoot for receiving the potatoes from said shovels and conducting them out of the machine, a flange at the end of the second cylinder preventing the potatoes from falling out, and a low truck to carry the sacks and the crew for attending the machine and sacks.

4. A potato-digging machine comprising a wheel frame, a plowshare supported by said frame, a skeleton cylinder fixed on said frame and adapted to receive potatoes released by said plowshare, said fixed cylinder being open at its rear end, and provided with a side opening, a longitudinal shaft supported on said frame and driven from the supporting wheels thereof, a rotary skeleton cylinder supported on said shaft and provided with an open forward end which registers with the open rear end of said stationary skeleton cylinder, a series of oblique blades supported by said shaft within said stationary cylinder and operative to pass the vines through said side opening and the potatoes through the rear end opening of said stationary cylinder into said rotary cylinder.

In testimony whereof I have affixed my signature.

OTTO LUDVIG ZEUTHEN.
